UNITED STATES PATENT OFFICE.

COURTLAND F. CARRIER, JR., OF ELMIRA, NEW YORK, ASSIGNOR TO ELMIRA ELECTRO-CHEMICAL COMPANY, OF ELMIRA, NEW YORK, A CORPORATION OF NEW YORK.

APPARATUS FOR ELECTROLYSIS OF BRINE.

No. 881,108.

Specification of Letters Patent. Patented March 10, 1908.

Application filed April 25, 1907. Serial No. 370,280.

To all whom it may concern:

Be it known that I, COURTLAND F. CARRIER, Jr., a citizen of the United States, residing at Elmira, in the county of Chemung 5 and State of New York, have invented certain new and useful Improvements in Apparatus for Electrolysis of Brine, of which the following is a specification.

The object of this invention is to provide 10 an apparatus for producing caustic alkali and chlorin by electrolysis of brine.

For a full understanding of the invention reference is made to the accompanying drawing, wherein:

15 Figure 1 is a plan view of a preferred form of apparatus, the covers and anodes being removed; Fig. 2 is a vertical section of the same on line 2—2 of Fig. 1; Fig. 3 is a vertical section of the same on line 3—3 of Fig. 20 1; and Fig. 4 is a vertical section of the same on line 4—4 of Fig. 1.

Referring to the drawings, 1 represents an electrolytic cell, preferably constructed of a unitary body of cement, concrete or the like, 25 and comprising an anode or decomposing compartment 2, and one or more oxidizing or caustic compartments 3, shown as two in number. The decomposing and oxidizing compartments are separated by partitions 4, 30 4, depending into slots 5, 5 in the bottom of the cell, and providing passage ways which in operation are sealed by mercury in the usual manner. The anode compartment 2 is provided with a gas-tight cover 6. The 35 anodes 7, comprising parallel horizontal bars of graphite, are supported by graphite lugs 8, 8 mounted in the cover 6.

9, 9 represent covers for the oxidizing compartments 3, provided with escape pipes 10 40 for hydrogen. It will be understood that the covers 9 may be omitted in case it is not desired to collect the hydrogen.

Brine is admitted to the decomposing compartment through pipe 11, disposed 45 immediately above the surface of the mercury; and spent brine and chlorin are withdrawn through pipe 12, located approximately at the level of the electrolyte. The precise level of the electrolyte in the anode 50 compartment may be controlled by means of a dam 13 within the pipe 12. Water is

admitted to the oxidizing compartments 3 through pipes 14, 14, and the caustic solution is withdrawn from said compartments through pipes 15, constructed to withdraw 55 the solution from points adjacent the level of the mercury.

Means are provided for maintaining a continuous circulation of the mercury through the decomposing and oxidizing compartments, such means comprising in the preferred embodiment of the invention a centrifugal pump 16, located in a pump-well 17 below the general level of the mercury in the decomposing and oxidizing compartments, 60 and adapted to be driven by bevel gears 18 or other suitable means. The pump-well 17 communicates through conduits 19 in the cell body 1 with the oxidizing compartments 3, said conduits 19 entering the well 17 below 70 the pump, in such manner as to permit the mercury to rise within the well, and to form therein a deep and effective seal capable under all conditions of preventing the caustic solution from the compartments 3 from passing with the mercury into the anode compartment. The pump 16 discharges through a conduit 20 within the cell body 1 and extending the entire length of the anode compartment 2. This conduit 20 communicates 80 with the anode compartment through a slot 21, preferably formed between adjacent edges of glass strips 22, 22 cemented into the base of the cell. The total area of the slot 21 should not exceed the cross sectional area 85 of the mercury conduit 20 adjacent the pump 16, in order to insure a flow of mercury throughout the entire length of the slot. The conduit 20 may be diminished in cross section in the direction of the flow of mercury. 90 This arrangement is adapted to provide an even flow of mercury over the entire surface of the floor of the anode compartment.

On the floor of the anode compartment are 95 cemented a number of triangular strips 23 of glass, slate or the like, disposed as shown in Fig. 1 with their apices directed toward the slot 21. These strips project slightly above the level of the mercury, and serve to 100 divide the mercury into a series of channels 24, each diminishing in superficial area and in

cross section in the direction of the mercury seals or passages 5.

The oxidizing compartments 3 are preferably provided with baffles 25, interposed 5 in the line of flow of mercury between the seals 5 and the return conduit 19, these baffles serving to prevent the rich amalgam from returning directly to the anode compartment. The cathode connection to the 10 mercury may conveniently be made through plates 26 of graphite, iron or the like arranged on the bottom of the oxidizing compartments; or in any other suitable manner. Any known or suitable means for accelerating 15 the oxidation of the alkali metal in the compartments 3 may be adopted, the arrangement of the apparatus being correspondingly modified; if for instance the amalgam is to be decomposed electrolytically, suitable cathodes may be supported 20 from the covers 9 as will be readily understood.

In order to adjust the cell in such manner as to provide a substantially even and regular flow of mercury over the entire floor of 25 the anode compartment, adjusting screws 27 are provided; as shown these screws 27 pass through supporting sills 28, conveniently of wood, and constituting a supporting 30 frame for the cement body of the cell.

In operation brine is supplied to the compartment 2 and water to the lateral compartments 3, and an electric current is caused to flow to the mercury in the anode 35 compartment; the mercury is set in motion, and flows regularly and continuously through the apparatus in the direction hereinbefore indicated.

In the operation of cells of the mercury 40 cathode type it is essential to the highest efficiency that the amalgam formed in the anode compartment be rapidly and completely removed therefrom; that the mercury be effectively circulated and evenly distributed beneath the anode; and that an 45 effective seal be maintained between the liquids in the decomposing and oxidizing compartments. The advantages of the present apparatus with particular reference to the accomplishment of these results are as follows:

(1) As the mercury becomes richer in sodium its flow tends to become sluggish, and sodium or the richer amalgam tends to 55 gather in patches upon the surface of the mercury and to enter again into solution in the anode electrolyte. The present construction provides mercury channels 24 diminishing in cross sectional area and in superficial area in the direction of flow of the 60 amalgam; in these channels therefore the velocity of flow of the amalgam tends to increase in the direction of its movement, and

thus to compensate for the retardation due to its progressive enrichment. By suitably 65 proportioning the strips 23 to the size and form of the anode compartment a substantially even and regular flow of the amalgam may be secured; or the velocity of the flow may be increased in the direction of the outlet. In practice it is preferred to so proportion the several elements that the flow of the mercury is accelerated substantially in 70 proportion to its enrichment in sodium.

(2) The provision of the central distributing slot 21 for the inflowing mercury secures 75 its even distribution beneath the anode.

(3) The deep seal constituted by the pump-well 17 and the conduits 19 communicating therewith is effective under all conditions of 80 operation or rest to prevent the passage of liquids lighter than mercury between the respective compartments.

I claim:

1. An electrolytic cell having decomposing 85 and oxidizing compartments, and means for circulating mercury therethrough, the passage for mercury through the decomposing compartment diminishing in superficial area in the direction of flow. 90

2. An electrolytic cell having decomposing and oxidizing compartments, and means for circulating mercury therethrough, the passage for mercury through the decomposing compartment diminishing in cross sectional 95 area and superficial area in the direction of flow.

3. An electrolytic cell having decomposing and oxidizing compartments, means for circulating mercury therethrough, and a distributing slot for mercury substantially centrally 100 disposed in the decomposing compartment.

4. An electrolytic cell having decomposing and oxidizing compartments, means for circulating mercury therethrough, a distributing slot for mercury substantially centrally disposed in the decomposing compartment, and means in said compartment for preventing retardation of the flow of the amalgam therein. 110

5. An electrolytic cell having decomposing and oxidizing compartments, means for circulating mercury therethrough, a distributing slot for mercury substantially centrally disposed in the decomposing compartment, 115 and means in said compartment for preventing retardation of the amalgam therein, said means comprising triangular strips or blocks extending above the surface of the mercury and providing intermediate channels 120 diminishing in cross sectional area in the direction of flow of the amalgam.

6. An electrolytic cell having decomposing and oxidizing compartments, a conduit for mercury substantially centrally disposed 125 beneath said decomposing compartment, and

a distributing slot between said conduit and compartment.

7. An electrolytic cell having decomposing and oxidizing compartments, a conduit for mercury substantially centrally disposed beneath said decomposing compartment, and a distributing slot between said conduit and compartment, the area of said slot not ex-

ceeding the cross sectional area of said conduit at its inlet end. 10

In testimony whereof, I affix my signature in presence of two witnesses.
